GAS-TIGHTENING DEVICES FOR OVEN DOORS

Felix Jean François Barbas, Paris, France

Application January 9, 1952, Serial No. 265,669

Claims priority, application France January 9, 1951

10 Claims. (Cl. 126—190)

This invention relates to gas-tightening devices for oven doors.

The object of the present invention is to provide a sealing means around an oven aperture which is combination with a sliding door for said aperture will hermetically seal said closure when said door is closed for preventing loss of heat or gases from said oven.

A further object of the present invention is to provide a slidable door for opening and closing over apertures including flowable sealing means around said aperture and alongside said door which means is retained in its sealing position regardless of the position of said door.

A sealing device according to the invention comprises, in combination, about the aperture to be closed, a permanent and uninterrupted chain of tightening material which may be housed in channels of any suitable shape provided about said aperture; on the door of said aperture, on the one hand, closing elements extending below said door with respect to the direction in which it opens and closing hermetically the portions of the aforesaid chain of tightening material that are parallel to that direction (whether the door is open or closed), and, on the other hand, closing elements which close the other portions of said chain, which are horizontal in the present case, when the door is closed only. The sections of the fixed channels provided about the aperture of the oven may be U- or V-shaped or otherwise. And the horizontal portions of said channels can normally be completely open when the door is open. While the vertical portions of said channels can be normally partly closed by fixed flexible or rigid plates, and in such a case, the corresponding movable members, integral with the door, may be sliding plates, in close frictional relation with said fixed plates, closing hermetically the free space formed between their edges and constantly preventing the tightening material from falling out of said channels, whether the door is closed or open.

As regards the vertical portions of the gas-tightening chain channels, their closing is then permanently ensured by sliding plates, moving with the door, before the front openings of these portions of said channels.

As regards the horizontal portions of the gas-tightening chain channels, their closing can be ensured by making the movable closing parts, integral with the door, penetrate inside the gas-tightening material filling said channels, but only when the door is shut as when the door is open, said horizontal channels keep open.

It should be pointed out that the vertical portions of the fixed channels of the gas-tightening chain must have a bottom adapted to retain the tightening material they contain.

It should also be pointed out that the prolongations of the vertical movable closing parts, integral with the door of the oven, in order to always ensure a satisfactory tightness on the sides of the aperture of the oven, will preferably have a length equal to the sum of the height of the corresponding vertical channels, the maxi-

2

mum opening height of the door and a sufficient safety height (such as a few cm.).

Packing boxes may be provided in the path of the vertical gas-tightening elements, on the travel of their prolongations.

As a tightening material, the following may be used

(1) if a comparative tightness is desired in the vertical portions of the fixed channels, a suitable movable, pulverulent or granular material, such as sand, plaster, kieselguhr or the like, or a mixture of these; and, in the horizontal portions of said fixed channels, a similar material or a pasty material, heat resistant, such as a plastic lubricating material, grease or the like, or a liquid substance, such as a high combustion point oil.

(2) if a perfect tightness is desired in the vertical portions of the fixed channels, a pasty material; and, in the horizontal portions of said channels, a pasty or liquid substance.

Actually, the provision in said channels of a granular or pulverulent material produces a substantial loss in the leakage of the gas, whereby a comparative tightness is obtained, while a pasty substance in a channel prevents any gas from passing through, the result thereof being an absolute tightness.

25 In the attached drawings, various embodiments of the invention have been illustrated by way of example, which are in no way limitative.

In the drawings:

Fig. 1 is an elevational view of the fixed portions of a 30 vertical tightening channel with its flexible plates.

Fig. 2 is a side-view of said complete channel providing a tight side contact with a sliding plate integral with the door, which has been supposed to be slightly open.

Fig. 3 is a sectional view along AA of Fig. 1, in which 35 the sliding plate and a portion of the door are shown in dash-and-dotted lines.

Fig. 4 is a semi-elevational view of an oven aperture, provided with a door opening upwardly and slightly open.

Fig. 5 is a sectional view along BB of Fig. 4.

Fig. 6 is a plan view of the aperture of the oven, without the door, in which the flexible plates are not shown.

Fig. 7 is a sectional view along CC of Fig. 4.

Fig. 8 is a plan view of a sliding plate packing box, and, above, a sectional view thereof along DD.

Fig. 9 is a perspective view of a portion of the 45 whole of the fixed part of the tightening device (in which the flexible plates are not shown).

Fig. 10 is a perspective view of the door provided with the movable part of the tightening device.

Fig. 11 is a perspective view of a gas-tightening device mounted upon an oven in accordance with the present invention.

Figs. 1 to 3 show a vertical tightening channel 1 provided on each side of the aperture of the oven, the fixed walls 2 of which have, in front thereof, flexible plates 3 forming between their free edges a longitudinal opening or mouth 4 (a, b, c, d, on Fig. 1). Said opening can be closed by a sliding plate 5 (Figs. 2, 3 to 8 and 10) integral with the door 6 in its sliding motion, which forms the movable part of the vertical tightening channel 1. Said channel 1 has a bottom 7 making it possible to fill it with a movable material (not shown on the drawings). When the movable plate 5 moves, it slides along the fixed flexible plates 3, whereby a tight contact is constantly ensured between the fixed walls 2 and the movable plate 5 of the vertical tightening channel 1, allowing the movable material contained by said vertical channel 1 to form a vertical permanent chain of movable material in spite of the displacements of the door 6.

70 A slot 8 (Figs. 2, 3 and 6) is made in the bottom 7 of the vertical channel 1, providing a passage for the

lower prolongation of the sliding plate 5 extending below the door 6, as shown specially on Figs. 4, 7 and 10, which, as the door is being raised, keeps pressing against the fixed plates 3 ensuring the gas-tightness of the closure of the channel 1. There is a certain play between said slot 8 and the plate 5; therefore a packing box 9 is provided at the lower part of the slot 8 (Fig. 8) the purpose of which is to allow the passage of the plate 5 but to avoid that of the movable material filling the channel 1 which might, were not such a packing box provided, flow into the interstice. Said packing box may comprise a rubber plate 10 through which the plate 5 can pass with a very small play which does not allow the movable material to flow through; said rubber plate 10 is laterally movable in its housing 11; owing to said packing 9, the slideable plate 5 is slideable in accordance with the displacements of the door, constantly ensuring permanent longitudinal closure of the vertical channel 1, which can thus permanently contain a movable material cooperating in the permanent gas-tightness along the lateral vertical parts of the door.

In the same way as the vertical channels 1 of the fixed device ensuring the gas-tightness can be filled up with a movable material, the aperture of the oven can be provided at top and bottom, with upper and lower horizontal channels 12 and 13 (Figs. 4, 6, 7 and 9) with joining channels 14 connecting the upper horizontal channel 12 to the upper part of the vertical channels 1 ensuring gas-tightness. Owing to the fact that these various channels, which are also filled with a movable material are permanently connected at their extremities, a permanent, endless chain of movable material is thus formed about the aperture of the oven.

The movable gas-tightening device integral with the door 6 also comprises at its upper part a plate 15 adapted to penetrate into the upper horizontal channels 12 and the connecting one 14, and at its lower part, a plate 16 adapted to penetrate into the lower horizontal channel 13 defined by walls 17 extending across in front of the oven between the walls 2. When the door 6 slides down to its closing position, the upper penetrating plate 15 penetrates into the upper horizontal channel 12 and the connecting channels 14 and also into the high parts of the vertical lateral channels 1 and ensures tightness by penetrating into the movable material contained in said channels; in the same way, at the lower part of the door 6, the lower penetrating plate 16 penetrates into the movable material that is in the lower horizontal channel 13; thus the desired gas-tightness is automatically obtained as soon as the fixed and the movable parts of the gas-tightening device are connected.

The above arrangements are given by way of example only: the shapes, sizes, details of structure and uses can be changed without departing from the characteristics of the invention.

The movable material used may be sand, plaster, kieselguhr, etc. . . .

In some cases, the horizontal channels can be filled with liquids, such as high combustion point oils, while the vertical channels are filled with materials insoluble in the liquids used; or screens, whether plastic or not, can also be placed in the connecting channels in order to separate these materials of different kinds. By so doing, a permanent endless chain is obtained about the aperture of the oven, said chain being formed of a pasty material in the vertical channels and of a pasty or liquid material in the horizontal channels, whereby a hermetical instantaneous closing of the door of the oven is provided. In some embodiments of the gas-tightening device, the vertical channels can be partly or completely suppressed and be replaced by a form the extremity of which, flexible or not, ensures a longitudinal contact with the sliding plate in a groove full with grease. The above processes and devices can be applied to any aperture that must be tightly closed.

What I claim is:

1. A sealing device for oven openings provided with vertically moving doors, comprising an oven having continuous channels provided around the entrance opening thereof, a permanent chain of sealing material positioned in said channels, spaced apart fixed plates partly closing the open front part of said channels, a door slidably mounted on said oven for closing and opening said oven opening, vertical closing members extending below said door with respect to its opening direction and slidably positioned across the mouth of the vertical portions of said channels in close contact with said plates in all vertical positions of said door for hermetically closing said vertical channels and said door having closing members for hermetically closing the remaining portions of said channels in the closed position of said door only.
2. A sealing device for oven openings provided with vertically moving doors, comprising an oven having vertical channels on either side of its entrance opening, closing means extending across the bottom of each of said channels, permanent chains of tightening materials positioned inside said channels, spaced apart fixed plates partly closing the open front part of said channels, said oven having further channels joined to said vertical channels so as to completely surround said oven entrance opening, a permanent chain of tightening materials positioned in said further channels, a door slidably mounted for vertical movement on said oven, vertical closing members extending below said door with respect to its opening direction and slidably positioned across said plates in close contact therewith in all vertical positions of said door for hermetically closing the space between said plates and the channels therewith and said door having closing members hermetically closing said further channels in the closed position of said door only.
3. A sealing device for oven openings provided with vertically moving doors, comprising an oven having vertical channels on either side of its entrance opening, closing means extending across the bottom of each of said channels, permanent chains of tightening materials positioned inside said channels, spaced apart fixed plates partly closing the open front part of said channels, said oven having further channels joined to said vertical channels so as to completely surround said oven opening, a permanent chain of tightening materials positioned in said further channels, a door slidably mounted on said oven for vertical movement for opening and closing said opening, vertical plates extending below said door with respect to its opening direction and in close frictional relation with said fixed plates in all vertical positions of said door for closing the space between said fixed plates, and said door having closing parts hermetically closing said further channels only in the closed position of said door.
4. A sealing device for oven entrance openings provided with vertically moving doors, comprising an oven having vertical channels on either side of its entrance opening, closing means extending across the bottom of each of said channels, permanent chains of tightening materials positioned inside said channels, spaced apart fixed plates partly closing the open front part of said channels, said oven having further channels joined to said vertical channels so as to completely surround said oven opening, a permanent chain of tightening materials positioned in said further channels, a door slidably mounted on said oven for vertical movement for opening and closing said opening, vertical plates extending below said door with respect to its opening direction and in close frictional relation with said fixed plates in all vertical positions of said door for closing the space between said plates, packing-boxes positioned at the bottom of said fixed plates and having said vertical plates extending therethrough and said door having closing parts hermet-

ically closing said further channels in the closed position of said door only.

5. A sealing device for oven entrance openings provided with vertically moving doors, comprising an oven having vertical channels on either side of its entrance opening, means providing a bottom for each of said channels, permanent chains of tightening materials positioned inside said channels, spaced apart fixed plates partly closing the open front part of said channels, said oven having further channels joined to said vertical channels so as to completely surround said oven opening, a permanent chain of tightening materials positioned in said further channels, a door slidably mounted on said oven for vertical movement and for opening and closing said opening, vertical plates extending below said door with respect to its opening direction and in close frictional relation with said fixed plates in all vertical positions of said door for closing the space between said fixed plates and plates carried by said door forming closing members and capable of penetrating into said tightening material contained in said further channels in the closed position of said door only.

6. A sealing device for oven entrance openings provided with vertically moving doors comprising an oven having channels surrounding in a continuous manner the entrance opening of said oven, a permanent chain of a movable tightening material positioned in said channels, spaced apart fixed plates partly closing the open front part of said channels, a door slidably mounted on said oven for vertical movement and for closing said opening, vertical closing members extending below said door with respect to its opening direction and extending across the mouths of the vertical portions of said channels in close contact with said plates in all vertical positions of said door for hermetically closing said channel mouths and said door having closing members for hermetically closing the remaining portions of said channels in the closed position of said door only.

7. A sealing device for oven entrance openings provided with vertically moving doors comprising an oven having channels surrounding in a continuous manner its entrance opening, a permanent chain of a movable tightening material positioned in vertical portions of said channels, a pasty tightening material positioned in the remaining portions of said channels, spaced apart fixed plates partly closing the open front part of said channels, a vertically slidable door mounted on said oven for closing said opening, vertical closing members extending below said door with respect to its opening direction and slidably positioned across the mouth of the vertical portions of said channels in close contact with said plates in all vertical positions of said door for hermetically closing said vertical channel mouths and said door having closing members for hermetically closing the remaining portions of said channels in the closed position of said door only.

8. A sealing device for oven entrance openings provided with vertically moving doors comprising an oven having channels surrounding in a continuous manner its entrance opening, a permanent chain of a movable tightening material positioned in the vertical portions of said channels, a liquid tightening material positioned in

the remaining portions of said channels, spaced apart fixed plates partly closing the open front part of said channels, a vertically slidable door mounted on said oven for opening and closing said opening, vertical closing members extending below said door with respect to its opening direction and extending across the mouths of the vertical portions of said channels in close contact with said plates in all vertical positions of said door for hermetically closing said channel mouths said door having closing members for hermetically closing the remaining portions of said channels in the closed position of said door only.

9. A sealing device for oven openings provided with vertically moving doors comprising an oven having channels surrounding in a continuous manner its entrance opening, a permanent chain of a pasty tightening material positioned in the vertical portions of said channels, a pasty tightening material positioned in the remaining portions of said channels, spaced apart fixed plates partly closing the open front part of said channels, a vertically slidable door mounted on said oven for closing said opening, vertical closing members extending below said door with respect to its opening direction across the mouths of the vertical portions of said channels in close contact with said plates in all vertical positions of said door for hermetically closing said channel mouths and said door having closing members for hermetically closing the remaining portions of said channels in the closed position of said door only.

10. A sealing device for oven openings provided with vertically moving doors comprising an oven having channels surrounding in a continuous manner its entrance opening, a permanent chain of a pasty tightening material filling the vertical portions of said channels, a liquid tightening material filling the remaining portions of said channels, spaced apart fixed plates partly closing the open front part of said channels, a door slidably mounted on said oven for vertical movement and for opening and closing said opening, vertical closing members extending below said door with respect to its opening direction and across the mouths the vertical portions of said channels in close contact with said plates for hermetically closing said channel mouths in all vertical positions of said door and said door having closing elements for hermetically closing the remaining portions of said channels when said door is in its closed position only.
